UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 8, 1921, Serial No. 490,505. Renewed June 25, 1925.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening cases or hoods, and is of the same general 10 type disclosed in my pending application, Serial No. 466,820, filed May 4, 1921.

The casing disclosed in said application comprises a body part and a cover part or 15 ceiling hinged to said body part. The latter is provided with a large front opening, through which the machine may be inserted into the casing, the banks of type-keys projecting forwardly from said casing after the 20 machine has been inserted, and a cover-plate being provided for closing the front opening. The edge of the cover part forms with an edge of the body part a slot at the front, through which the various carriage- 25 operating members, such as the line-space lever, the carriage-return finger-piece, and the carriage-release lever, extend; sound-deadening means in the form of co-operating strips or cushions on the body part and 30 cover part being provided for closing the slot. The casing is provided with lateral extensions at the sides, in which the type- 35 writer-carriage operates to the right and left, said casing thus completely enclosing the noise-producing parts of the machine.

The sound-deadening casing of this invention is in the nature of an improvement on my application, Serial No. 488,302, filed

July 29, 1921, in which the casing is especially adapted for typewriting machines having long carriages, the lateral extensions being detachable from a main or central section of the casing, so that they may be replaced by extensions of different lengths, 45 according to the length of the carriage on the machine, said extensions being also detachable so that the casing occupies a minimum of space when the machine is not in use and further to provide clearance when 50 the machine is mounted upon a swingable base of a drop-head desk, so as not to interfere with the lowering of the machine with the casing into the desk.

An object of the present invention is to 55 provide lateral extensions which may read-

ily be adjusted to vary the length thereof according to the length of the typewriter-carriage and which may readily be collapsed to clear the top of the desk without removing them from the casing when it is 60 desired to lower the typewriting machine and casing into the desk. To this end, each lateral extension is comprised of several telescoping members sliding one in the other. Thus, there is avoided the necessity of removing the casing when the total width of 65 the latter with its extensions in use exceeds the width of the swingable base upon which the machine is mounted, in order that the machine may be swung to the interior 70 of the desk.

Only the main or central section comprises a separate body part and cover part, and the slot formed at the front between these parts is not continued into the extensions. If the line-space handle and carriage-release lever occupy their usual positions near the ends of the carriage, they would extend beyond the slot in the main section when the carriage travelled to the 80 right and left, and it would be necessary to continue to slot into the extensions. This invention provides means whereby the carriage may be returned and the line-space mechanism and carriage-release lever operated from outside the casing, said means being mounted on the typewriter-carriage near the center portion, so that travel of the carriage to the right or left will not carry the operating means beyond the slot in the 85 main section.

Other features and advantages will hereinafter appear.

In the accompanying drawings,

Figure 1 is a front elevation, partly sectioned, of the casing applied to an Underwood standard typewriting machine.

Figure 2 is a front elevation of the front bar of the typewriter-carriage and showing the line-space-handle-operating means and 100 the carriage-release-lever-operating means applied to said front bar.

Figure 3 is a plan view, partly sectioned, of the device shown in Figure 1.

Figure 4 is a plan view of the front cover- 105 plate disassembled from the casing.

Figure 5 is a side view, vertically sectioned, along the line 5—5 of Figure 1.

Figure 6 is a side view, vertically sectioned, along the line 6—6 of Figure 1. 110

The Underwood standard typewriting machine comprises a main frame 10 supported by feet 11 upon a base, said main frame having a forward extension 12 in 5 which are positioned banks of keys 13 operating type-bars, not shown, to cause types carried by said type-bars to print against a platen 16 journaled in the end walls 17 of a platen-frame 18. Said frame forms 10 parts of a carriage 20 mounted for letter-feeding movement upon a front rail 19 and a rear rail 21 on the main frame 10. The platen may be rotated in either direction by knobs or finger-wheels 24 fixed upon a 15 shaft 25, upon which the platen is mounted, or in line-spacing direction by the usual line-space mechanism, of which slide 26 and line-space lever 27 are shown. The carriage may be released from the usual escapement 20 devices (not shown) by the usual forward-ly-extending carriage-release lever 28.

For deadening the sounds arising in the typing operation, there is provided a sound-deadening casing or hood comprising a main 25 or central section, indicated generally by the numeral 40, and auxiliary sections, indicated generally by the numeral 41, forming lateral extensions of said main section. Said main section comprises a body part 42 and a cover 30 part 43 hinged at the rear to said body part, said body part comprising a rear wall 45, short side walls 46 and a front wall in the form of two end sections 47, said end sections being spaced apart to provide a 35 large front opening through which the machine may be inserted into the casing. The side walls 46 are provided with short horizontal extensions 50, so that the total width of the main section 40 is substantially the 40 same as the width of the machine when the carriage herein shown is centrally positioned. The machine is positioned within the casing by means of abutments 52 fixed to the rear of the body part, the forward 45 extension 12 extending forwardly from said casing to expose the banks of keys. To close all of the front opening not occupied by the forward extension 12, there is provided a cover-plate 53, which is mounted upon the 50 end portions 47 by means of latches 54 operated by turn-buttons 55, said latches being passed through similarly shaped openings 56 in the end portions 47, and then turned until they catch behind said end portions to 55 fix the cover-plate in position on the end portions 47. The machine is thus enclosed at the rear, front, and partly at the sides by the short side walls 46, and, to close said machine at the top, there is provided the cover part 43 having a ceiling 58 extending forwardly and downwardly and terminating in a short front wall 59, said ceiling being provided with a window or transparent plate 60 to permit the machine on the interior of the casing to be viewed. The front

wall 59 terminates some distance above the top of cover-plate 53, and thus forms a slot, through which various carriage-operating mechanisms (to be hereinafter described) may pass, and, to close all of the slot not 70 actually occupied by these mechanisms, there are mounted upon said front wall 59 and said cover-plate 53 co-operating strips or cushions 61 and 62, the two-ply edges of said cushions being clamped between co-operating members 63 to form units which are mounted upon said front wall and said cover-plate, respectively. 75

It will be obvious from the drawings that, when the machine is positioned within the main casing 40, operation of the machine will cause the carriage to move to the right or left, and, hence, beyond the open sides of said main section. To provide means for closing the open sides of said main section and permit the carriage to travel freely therein, there are provided the lateral extensions 41, having open inner ends which fit into the open sides of the main casing 40 and closed outer ends to prevent passage of sounds therethrough. When the machine is not in use, it is frequently desirable to reduce the amount of space occupied by the casing. This is particularly desirable when the casing is applied to a typewriting machine mounted upon the swingable base of a drop-head typewriter desk, in which case it is sometimes found that the total width of the casing exceeds the width of the swingable base, and, hence, it is necessary to remove the casing when it is desired to lower the machine to the interior of the desk. In order to render it unnecessary to remove the casing when it is desired to lower the machine, the lateral extensions 41 are collapsibly constructed of telescoping sections 64, which may be slid into one another, all of said sections being slidable into the main casing 40, and, since the latter is of substantially the same width as the typewriting machine, the casing and machine may be lowered together into the interior of the desk. When the machine and casing are raised, it is only necessary to pull out the telescoping sections of the extensions 41, and the machine and casing are in their operative positions. To mount the side extensions telescopically within one another and within the main casing 40, each section 64, which is open at its outer end, is provided at its outer end with inwardly-turned flanges 65 which slide along the outer surface of the next smaller member, and with outwardly-turned flanges 66 which slide on the inner surface of the next larger member and serve as limiting stops for the inwardly-turned flanges 65. The telescoping section which slides upon the main section of the casing would not have a guiding surface at the top when the cover part was raised, unless a 130

fixed surface were provided, upon which the flanges of said telescoping member could slide. This fixed surface is provided in the form of two end pieces 70, having inwardly-turned flanges 71 with which the outwardly-turned flanges 66 of the first, or innermost, telescoping member, co-operate. Stops 72 may be detachably mounted on the inner surfaces of the main section and of each telescoping member to limit the inward movement of the respective telescoping member fitting therein. The main section of the casing and each telescoping member are lined with sound-deadening material 73, into which slots 74 are cut to permit flanges 66 to slide in contact with the inner surfaces of the members and main section. To permit the telescoping members to be drawn out of the main section, there are provided finger-pieces 75, which also support said lateral extensions upon a base, said finger-pieces 75 being pivotally mounted at 76 upon the extensions, and being swingable to effective and ineffective positions, in which positions they are held by spring-detents 77 (Figure 6), carried by said extensions and engaging in openings 78 and 79, respectively, in the finger-pieces.

It is desirable to provide means independent of the casing whereby the line-space mechanism and carriage-release lever may be operated and the carriage returned from the exterior of the casing, so that the ordinary typing operations may be carried on without raising the cover or removing any part of the casing. However, if the line-space lever 27 and carriage-release lever 28 were extended directly forward to pass through the front slot and between the cushions 61, it would be necessary to extend the slot into the extensions 41, since the lever 27 and lever 28 are mounted near the ends of the typewriter-carriage, and, upon movement of the carriage to the right or left of its center position, these elements would pass beyond the main casing 40 and into the extensions 41. In order to simplify the construction of the casing, it is not desirable to extend the slot into the extensions 41, and, therefore, the line-space lever 27 and carriage-release lever 28 are not extended forwardly but terminate within the casing. To operate said line-space lever 27, there is provided a laterally-positioned link or bar 85 having a hook 86, engaging the left-hand side of the lever 27, said link being positioned in guide-members 87 fixed to the front bar of the carriage and operable laterally by means of a finger-piece or handle 88 fixed to said bar and extending forwardly through the front slot. Since the handle 88 may be fixed to said link at any point, it is preferably attached near the central portion of the front bar of the carriage, so that the movement of the carriage to the right or left will, therefore, not carry the handle 88 beyond the ends of the main section 40, and, hence, not beyond the ends of the front slot. To operate the carriage-release lever by means which is likewise positioned near the central portion of the front bar of the carriage and which extends forwardly through the front slot, there is provided a lever 90, pivoted in ears 91 struck up from a bracket 92, fixed to the front bar of the carriage, the rear end of said lever having an inwardly-turned lip 90a to engage under one end of a lever 93, to operate the latter about a pivot 94 on the bracket 92, so that downward movement of the front of lever 90 will cause downward movement of one end 95 of lever 93, said end being in contact with release lever 28 to depress the latter when lever 90 is operated. The spring which normally presses the release lever 28 upwardly will be sufficient to restore the levers 90 and 93 to their normal positions when the operator releases lever 90. Similarly, a carriage-return finger-piece 96 may be fixed to the central portion of the front bar of the carriage to extend forwardly through the front slot, so that operation of the carriage to the right or left will not carry finger-piece 96 beyond the ends of the front slot.

Variations may be resorted to within the scope of the invention, and portions of the improvements may be used without others. Having thus described my invention, I claim:

1. A sound-deadening casing for a type-writing machine having a carriage, said casing comprising a central section to contain the machine when the carriage is in central position and extensible end sections so constructed that they may be extended for typing, and may be left in extended condition to accommodate the travel of the carriage and, when the typing is completed and the carriage returned to its normal position, may be pressed inwardly to collapsed condition. 100

2. A sound-deadening casing for a type-writing machine having a carriage, said casing comprising a central section to contain the machine when the carriage is in central position and extensible end sections comprising telescoping members so constructed that when drawn out, preparatory to typing, to accommodate the travel of the carriage, they will remain in extended condition as long as desired, and, upon completion of the typing and return of the carriage to its central position, may be pressed inwardly to collapsed condition, each telescoping member adjacent the central section being slid- 105

able into the latter. 110

3. A sound-deadening casing for a type-writing machine having a carriage, said casing comprising a central section to contain the machine when the carriage is in central 115

position and extensible end sections comprising telescoping members so constructed that when drawn out, preparatory to typing, to accommodate the travel of the carriage, they will remain in extended condition as long as desired, and, upon completion of the typing and return of the carriage to its central position, may be pressed inwardly to collapsed condition, each telescoping member adjacent the central section being slid- 120

able into the latter. 125

4. A sound-deadening casing for a type-writing machine having a carriage, said casing comprising a central section to contain the machine when the carriage is in central 130

position and extensible end sections so constructed that, when drawn out to extended condition to accommodate the travel of the carriage, they will remain in such condition 5 until collapsed manually, said end sections being so mounted that, when collapsed, they may be slid into said central section.

4. A sound-deadening casing for a typewriting machine having a carriage, said 10 casing comprising a central section to contain the machine when the carriage is in central position and end sections comprising telescoping members movable outwardly to form extensions of said central section 15 to accommodate the travel of the carriage and movable inwardly to collapse said end sections to economize space when the machine is not in use, and means for limiting the outward movement of said telescoping members, said means comprising oppositely-turned flanges on the inner and outer edges of said members, the flanges on the inner edges of said members co-operating with the flanges on the outer edges of the 20 adjacent members to limit the outward movement of said members.

5. A sound-deadening casing for a typewriting machine having a carriage, said 30 casing comprising a central section to contain the machine when the carriage is in central position and end sections comprising telescoping members movable outwardly to form extensions of said central section and movable inwardly to collapse said end 35 sections to economize space when the machine is not in use, and means for limiting the outward movement of said telescoping members, said means comprising outwardly-turned flanges on the inner ends of 40 said members and inwardly-turned flanges on the outer ends of said members, the outwardly-turned flanges of said members engaging the inwardly-turned flanges of the adjacent members to limit the outward 45 movement of said members.

6. A sound-deadening casing for a typewriting machine having a carriage, said 50 casing comprising a main section into which the machine is inserted and which has open sides, extensions mounted on the sides of the main section and comprising telescoping members, the members nearer the main section being open at both sides to permit the carriage to operate therein, and the members 55 farthest from the main section being closed at their outer sides to prevent escape of sound through said extensions, and means carried by said outermost member for extending and collapsing said extensions and 60 for supporting the outer ends of said extensions upon the support for said machine and said casing.

7. A sound-deadening casing for a typewriting machine having a carriage, said 65 casing comprising a main section into which

the machine is inserted and which has open sides, extensions mounted on the sides of the main section and comprising telescoping members, the members nearer the main section being open at both sides to permit the carriage to operate therein, and the members farthest from the main section being closed at their outer sides to prevent escape of sound through said extensions, and a combined finger-piece and support for moving the telescoping members of each extension and for supporting the outer ends of said members upon the support for said machine and said casing, said finger-pieces and supports being mounted on said extensions and swingable to effective and ineffective positions. 70

8. A sound-deadening casing for a typewriting machine having a carriage, said 75 casing comprising a main section into which the machine is inserted and which has open sides, extensions mounted on the sides of the main section and comprising telescoping members, the members nearer the main section being open at both sides to permit the carriage to operate therein, and the members farthest from the main section being closed at their outer sides to prevent escape of sound through said extensions, and a combined finger-piece and support for moving the telescoping members of each extension and for supporting the outer ends of said members upon the support for said machine and said casing, said finger-pieces and supports being pivotally mounted on 80 said outermost member and swingable to effective and ineffective positions, and means carried by each of said members, closed at their outer sides, for holding the corresponding finger-piece and support in effective or ineffective position. 90

9. The combination with a sound-deadening casing for a typewriting machine, said 95 casing comprising a main section into which the machine is inserted, said main section having open sides and having a slot, said machine having a carriage and various operating levers on said carriage, said carriage and levers operating to the right and left beyond said open sides, and extensions mounted upon said open sides and in which said carriage and levers operate, of means independent of the casing and extending to the outside of the casing for operating said levers, said means being connected to said levers to operate in said slot in all 100 positions of the carriage. 105

10. The combination with a sound-deadening casing for a typewriting machine, said 110 casing comprising a main section into which the machine is inserted, said main section having open sides and a slot at the front, said machine having a carriage and various operating levers mounted on said carriage near the ends thereof, the ends of said car- 115

riage operating to the right and left beyond said open sides, the central portion of said carriage operating at all times within the main section, and extensions mounted

5 upon said open sides and in which said levers operate, of means independent of the casing for operating said levers, said means extending to the outside of said casing and being mounted on the central portion of 10 the carriage to operate at all times within the limits of said main section, said means being connected to said levers and operating in said slot in all positions of the carriage.

11. The combination with a sound-deadening casing for a typewriting machine, said casing comprising a main section into which the machine is inserted, said main section having open sides and a slot at the front, said machine having a carriage comprising 20 a carriage-release lever mounted thereon, said carriage-release lever operating beyond the main section, the central portion of said carriage operating at all times within the main section, and extensions mounted upon 25 said open sides and within which said carriage and release lever operate, of means for operating said release lever, said means extending to the outside of said casing and being mounted on the central portion of the 30 carriage to operate at all times within the limits of said main section, said means being connected to said release lever and operating in said slot in all positions of the carriage.

35 12. The combination with a sound-deadening casing for a typewriting machine, said casing comprising a main section into which the machine is inserted, said main section having open sides and a slot at the front, said machine having a carriage comprising 40 a carriage-release lever mounted thereon, said carriage-release lever operating beyond the main section, the central portion of said carriage operating at all times within the main section, and extensions mounted upon 45 said open sides and within which said carriage and release lever operate, of means for operating said release lever, said means comprising a lever extending to the outside 50 of said casing and pivotally mounted on the central portion of the carriage to operate at all times within the limits of said main section, said lever being connected to said release lever and operating in said slot in 55 all positions of the carriage.

60 13. The combination with a sound-deadening casing for a typewriting machine, said casing comprising a main section into which the machine is inserted, said main section having open sides and a slot at the front, said machine having a carriage comprising 65 a carriage-release lever mounted thereon, said carriage and release lever operating beyond the main section, the central portion of said carriage operating at all times with-

in the main section, and extensions mounted upon said open sides and within which said carriage and release lever operate, of means for operating said release lever, said means comprising a lever extending to the outside 70 of said casing and pivotally mounted on the central portion of the carriage to operate at all times within the limits of said main section, and a second lever pivotally mounted on said carriage and connecting said first lever and said release lever so that operation of said first lever operates said release lever, said first lever operating in said slot in all positions of the carriage. 75

14. A sound-deadening casing for a typewriting machine having a carriage, said casing comprising a central section and collapsible end sections or extensions so constructed that they may be adjusted to lengths sufficient to accommodate the travel of the 80 carriage and such adjustment may be retained as long as desired. 85

15. A sound-deadening casing for a typewriting machine, said casing comprising a central section and end sections or extensions in which the carriage of the typewriting machine may operate, each end section having a closed outer end, said end sections being adjustable to vary their length so that their closed outer ends may assume and remain, in positions slightly beyond the range 90 of travel of the carriage. 95

16. The combination with a sound-deadening casing comprising a main section, said main section having open sides and a slot extending from side to side thereof, said machine having a carriage and a line-space operating lever on said carriage, said carriage and lever operating to the right and left beyond the open sides of the main section, and end sections mounted upon the open side of the central section and in which the carriage and said lever operate, of means mounted on said carriage independent of 100 said casing, said means extending to the outside of the casing and being connected to 105 said line-space lever. 110

17. A sound-deadening casing for a typewriting machine having a carriage, said casing comprising a central section to contain the machine, lateral extensions of said central section comprising telescoping members to enable said extensions to be adjusted to lengths to accommodate the travel of the carriage, and linings of sound-deadening 115 material for each of said members. 120

18. A sound-deadening casing for a typewriting machine having a carriage, said casing comprising a central section to contain the machine, lateral extensions of said central section comprising telescoping members to enable said extensions to be adjusted to lengths to accommodate the travel of the carriage, linings of sound-deadening 125 material for each of said members, and means to 130

limit the outward movement of said members comprising an inwardly projecting flange at the outer end of each member open at its outer end and short flanges extending 5 outwardly from the inner end of the next member to engage the first flange when the extensions are fully extended, the lining of each member in which another is telescoped being grooved to accommodate the short 10 flanges.

19. The combination with a typewriter comprising a carriage, a platen journaled therein and a line-space lever at one end of said carriage, of an actuator for said line-space lever for use in connection with a sound-deadening casing enclosing the machine and having at its front a slot normally closed by cushioning members on opposite sides thereof, said actuator comprising 15 a slide mounted on the front part of the carriage and having a hook to engage the line-space lever, and a handle near the middle of the carriage and extending forwardly through said slot.

20. A sound-deadening casing for a typewriting machine having a carriage, said casing comprising a main part, members slideable on said main part for movement outwardly at each side to form closed extensions of said main part to accommodate the 25 travel of the carriage and slideable inwardly to compact form when the machine is not

in use, and supports pivoted on said members for movement into position to support the outer ends of said extensions. 35

21. A sound-deadening casing for a typewriting machine having a carriage, said casing comprising a main part, members slideable on said main part for movement outwardly at each side to form closed overhanging extensions of said main part to accommodate the travel of the carriage and slideable inwardly to compact form when the machine is not in use, sound-deadening material between said main part and said slideable members to prevent the escape of sound and to hold them by friction in any positions in which they may be placed, and supports for the outer ends of said extensions. 40

22. The combination of a typewriting machine having a carriage and a platen therein, a sound-deadening casing for said machine having a horizontal slot at the front thereof, and means extending through said slot and traveling therealong, substantially opposite the middle of said carriage at all times, for line-spacing said platen and releasing said carriage. 45
